OTHER PUBLICATIONS

Office Action along with the Notice of References Cited for Design U.S. Appl. No. 29/406,615 mailed on Oct. 11, 2012.

Primary Examiner — Karen E Eldridge Powers*(74) Attorney, Agent, or Firm* — Ladas & Parry LLP**CLAIM**

The ornamental design for a display screen with graphical user interface, as shown and described.

DESCRIPTION

The sole FIGURE is a front view of a display screen with graphical user interface.

The rectangular broken line depicting a display screen forms no part of the claimed design. The words and numbers shown in broken lines are unclaimed features of the graphical user interface.
